(57) **CLAIM**

We claim the ornamental design for a beverage dispenser, as
shown and described.

DESCRIPTION

FIG. 1 is a top perspective view of a beverage dispenser
showing my new design, with a portion partially broken away
for ease of illustration;

FIG. 2 is a bottom perspective view thereof;

FIG. 3 is a left side view thereof;

FIG. 4 is a right side elevation view thereof;

FIG. 5 is a front view thereof;

FIG. 6 is a back view thereof;

FIG. 7 is a top plan view thereof;

FIG. 8 is a bottom plan view thereof; and,

FIG. 9 is an environmental perspective view thereof.

The broken lines in the drawings are for illustrative purposes
only and form no part of the claimed design.
